UNITED STATES PATENT OFFICE.

ELLSWORTH JOSEPH EDWARDS, OF LOS ANGELES, CALIFORNIA.

ROLLER-BEARING.

No. 859,806.

Specification of Letters Patent.

Patented July 9, 1907.

Application filed July 10, 1906. Serial No. 326,480.

To all whom it may concern:

Be it known that I, ELLSWORTH JOSEPH EDWARDS, a citizen of the United States, and a resident of Los Angeles, in the county of Los Angeles and State of California, have invented a new and Improved Roller-Bearing, of which the following is a full, clear, and exact description.

My invention relates to improvements in roller-bearings, and more particularly to an improved means for 10 spacing and guiding the rollers and for carrying the end thrust, and its object is to provide the same with certain new and useful features hereinafter more fully described and particularly pointed out in the claims.

Reference is to be had to the accompanying drawings which form part of this specification, in which similar characters of reference indicate corresponding parts in the several views, and in which

Figure 1 is a longitudinal section through an axle and wheel, illustrating one form which my invention may 20 assume; Fig. 2 is a plan view of the skeleton frame used to space the rollers and showing the same before it is applied; Fig. 3 is an end elevation of the rollers and skeleton frame; Fig. 4 is a transverse sectional view through the rollers adjacent their ends, and more clearly 25 illustrating the manner in which they are supported in the frame; Fig. 5 is a longitudinal section through a modified form of my invention; Fig. 6 illustrates my invention as affixed to a car axle; Fig. 7 is an end elevation partly in section of the form shown in Fig. 6; 30 and Fig. 8 is a longitudinal section through a modified form of boxing to be used in connection with the form illustrated in Figs. 6 and 7.

Referring to the drawings in which similar numerals refer to similar parts throughout the several views, I 35 have shown in Fig. 1 my invention as applied to a common form of vehicle wheel 1 adapted to rotate on the spindle 2. The hub 3 of the wheel carries two telescoping tubes 4, 5 having shoulders 4', 5' between which the part 6 of the hub is securely held. Pins or projections 40 7 may be used if desired, to prevent rotation of the tubes independent of the hub. The outer ends of the tubes are enlarged and the inner surface of the enlarged portions constitutes a cylindrical bearing for the rollers, hereinafter to be described, and the inner end of each 45 of said enlarged portions is cut at an angle to form a beveled bearing surface for the ends of the rollers.

The axle shown is the common form of vehicle axle having a tapering spindle 8, and in order to provide a cylindrical bearing surface I secure a cylindrical bearing sleeve 9 to the spindle. A suitable spacing collar 50 10 is used on the reduced end of the spindle, to fill the space between the spindle and sleeve and hold the two rigidly together. At the ends of the bearing sleeve 10 are beveled washers 11, 12 and dust guard washers 13, 14 55 which may be provided. Between these, thin washers 15 may be used if found necessary to adjust the parts by advancing

the beveled washers when worn. Around each bearing sleeve near the ends thereof and inclosed within the enlarged ends of the telescoping tubes 4 and 5, are the rollers 16 and their spacing and guiding means 17, 60 which constitute an important part of my invention and which will now be described. Each roller 16 has a cylindrical intermediate portion 18 constituting the main bearing surface, a rounded end 19 and a reduced spindle 20 between the main body and the ends. The 65 spacing and guiding means 17 for the rollers may be formed in various ways, but in the preferred form and the one illustrated, it is formed of two strips of sheet metal having rectangular openings punched therein throughout its length as shown in Fig. 2. The two side 70 portions 22 are connected by cross-pieces 21 and between each two cross pieces each side portion is crimped to form half of a journal box for the spindles 20 of the rollers 16, leaving one side of each cross piece 21 in the plane of the centers of the rollers. Two of these strips or 75 skeleton frames are used, and the two are riveted or otherwise secured together at suitable intervals one inside of the other, so as to hold the rollers in an annular row with the spindles of each roller held between the side portions 22, and the main portion 16 of each roller 80 extending through the rectangular openings between the cross pieces 21. The cross pieces of one or both of the strips 17 may be omitted, leaving merely two rings having crimped or bowed portions to act as journal boxes for the spindles of the rollers.

85 The conical or rounded ends of the rollers bear against the beveled removable washers 11, 12, and the beveled shoulders of the telescoping tubes 4, 5, thus the ends of the rollers take up any end thrust of the wheel in respect to the axle, and by having the ends 90 of the rollers rounded and the washers and shoulders beveled, the place of contact of the two is brought away from the center of the roller, thereby producing less friction and distributing the wear on the roller to a line around the end of the same rather than limiting it 95 to a point at the center of the end, as would be the case were the faces of the washers 11, 12 at right angles to the axes of the rollers. The dust guard washers 13, 14 are preferably cut away slightly around their circumference, so that they fit partially within the ends of the 100 tubes 4, 5, making a more perfect seal against the entrance of dust and dirt. The end 24 of the spindle preferably extends beyond the end of the bearing sleeve 9, and by providing this end with screw threads and a nut 25, all the parts may be securely held together. 105 Freedom from lateral movement may be secured by using the washers 15, the thickness and number of which may be varied as the parts wear away.

110 Various changes may be made in the specific construction of my invention without departing from the spirit of my invention, one of such modified forms of my invention being illustrated in Fig. 5, in which the

spindle 8 is shown as being cylindrical rather than tapering, and in this case no bearing sleeve is required, the rollers contacting directly with the surface of the spindle. A modified form of construction is shown 5 for taking the end thrust, wherein the ends of the rollers are provided with sockets 26 having balls 27 therein, the said balls bearing against shoulders and washers at right angles to the axes of said rollers.

I adapt my improved bearing to the axle of a car 10 wheel in the manner illustrated in Figs. 6 to 8 inclusive. The beveled washer 28 fits on the car axle 29 adjacent to the car wheel 30, and against this washer surrounding the end of the axle is the row of rollers spaced and held in place in the manner illustrated in Figs. 1 to 4. 15 The boxing 31 has a cylindrical recess fitting over the end of the car axle and rollers, and at the inner end of this recess is a beveled washer 32 contacting with the outer end of the rollers. The boxing is firmly secured in the frame of the car truck 33 by bolts 34, 34, or in any 20 suitable manner. If desired, the boxing may be made in two parts as shown in Fig. 8, where one part may be detached on the line 35 without necessitating a complete separation of the parts.

By means of the novel structure hereinbefore described, the rollers serve the double function of acting 25 as bearings and also in taking all end thrust. By supporting the rollers at both ends, they are always kept in alignment and in their proper place, and it is impossible for one end of any roller to get ahead of the other.

Having thus described my invention, I claim as new and desire to secure by Letters Patent:

1. A roller bearing, comprising a plurality of telescoping tubes, there being an outwardly-facing beveled shoulder in 35 each of said tubes, a plurality of parallel rollers in one of said tubes and having the inner ends thereof contacting with the beveled shoulder of said tube, and a plurality of parallel rollers in a second tube, and having their inner ends contacting with the beveled shoulder of said second 40 tube.

2. A roller bearing, comprising a plurality of telescoping tubes, each having an outwardly-facing beveled shoulder, a plurality of parallel rollers in each of said tubes and having the inner ends of the rollers in each tube contacting 45 with the beveled shoulder in said tube, an axle in contact with the cylindrical surfaces of all of these rollers, and means carried by the axle and contacting with the outer ends of all of said rollers.

3. A roller bearing, comprising a plurality of telescoping 50 tubes, each having an outwardly-facing beveled shoulder, a plurality of parallel rollers in each of said tubes, the inner ends of said rollers being rounded and in contact with the beveled shoulders of the respective tubes, an axle surrounded by the rollers in each of said tubes and contacting 55 with the cylindrical surfaces thereof, means carried by said axle for contacting with the outer ends of said rollers, and means for spacing and holding each of said rollers in place.

4. In combination, an axle having a cylindrical bearing 60 surface, a hub having an axle-passage therethrough, two telescoping tubes extending into said passage from opposite ends, each of said tubes being provided with enlarged ends, means for contacting with the opposite sides of said hub, the inner surface of each of said tubes intermediate 65 the body portion and the enlarged ends being beveled, a

plurality of rollers having rounded ends located in the enlarged portion of each of said tubes and in contact with the inner surface thereof and the bearing surface of the axle, and having their inner ends in contact with said beveled portions, beveled washers carried by said axle and in contact with the outer rounded ends of said rollers, and means spacing said rollers and holding them parallel. 70

5. A plurality of cylindrical rollers, and means for supporting and spacing said rollers, said means comprising two telescoping skeleton frames, between which said rollers 75 are journaled, and each of said frames having openings through which the main portion of each of said rollers extends.

6. A plurality of rollers, means for supporting and spacing said rollers, said means comprising two telescoping 80 skeleton frames, between which said rollers are journaled, each frame having openings through which the main portions of said rollers extend, and crimped portions forming bearings for supporting said rollers.

7. A plurality of rollers, having spindles adjacent the 85 ends thereof, a skeleton frame having rectangular openings therein for the body portions of said rollers and crimped portions adjacent the opposite sides of each of said openings and adapted to receive said spindles, and means coacting with said skeleton frame for holding said spindles 90 in said crimped portions.

8. A plurality of rollers, having rounded ends and spindles adjacent the ends thereof, and two telescoping skeleton frames provided with rectangular openings adapted to receive the body portions of said rollers, the sides of said 95 skeleton frames adjacent the opposite sides of each of said openings being crimped to form bearings for the spindles of said rollers.

9. A plurality of rollers having spindles adjacent the 100 ends thereof, a skeleton frame having openings therein for the body portions of said rollers, there being bearings adjacent the opposite sides of each of said openings and adapted to receive said spindles, and means coacting with said skeleton frame for holding said spindles within said bearings. 105

10. In combination, a spindle, a tube surrounding said spindle, a plurality of parallel cylindrical rollers intermediate said tube and said spindle and having their cylindrical surfaces in contact with both, the ends of said rollers being rounded, means carried by the spindle and presenting a beveled face in contact with one end of said rollers, there being means carried by the tube and presenting a beveled face in contact with the opposite end of said rollers. 110

11. In combination, a spindle, a tube surrounding said 115 spindle, a plurality of parallel cylindrical rollers intermediate said tube and said spindle and having their cylindrical surfaces in contact with both, the ends of said rollers being rounded, means carried by the spindle and presenting a beveled face in contact with one end of said rollers, there being means carried by the tube and presenting a beveled face in contact with the opposite end of said 120 rollers, and means carried by said rollers for spacing the same.

12. A roller bearing, comprising a plurality of telescoping tubes, each having an outwardly-facing beveled shoulder, a plurality of parallel cylindrical rollers in each of said tubes, the inner ends of the rollers in each tube contacting with the beveled shoulder in said tube, an axle in contact with the cylindrical surfaces of all of said rollers, and means carried by the axle and presenting a beveled 125 face in contact with the outer ends of all of said rollers. 130

In testimony whereof I have signed my name to this specification in the presence of two subscribing witnesses.

ELLSWORTH JOSEPH EDWARDS.
